UNITED STATES PATENT OFFICE.

WILLIAM VITZTHUM, OF HOBOKEN, NEW JERSEY, ASSIGNOR TO MAX KATZENBERG, G. GARSON FREUND, AND MAX FREUND, OF NEW YORK, N. Y.

DESIGN FOR A BELT-BODY OR SIMILAR ARTICLE.

SPECIFICATION forming part of Design No. 33,567, dated November 13, 1900.

Application filed October 19, 1900. Serial No. 33,657. Term of patent 3½ years.

To all whom it may concern:

Be it known that I, WILLIAM VITZTHUM, a citizen of the United States, residing at Hoboken, county of Hudson, and State of New Jersey, have invented and produced a new and original Design for Belt-Bodies and Similar Articles, of which the following is a specification.

My invention relates to belt-bodies; and the essential feature of said invention resides in the shape and configuration of the article herein shown and described.

In the drawings forming part of this specification, Figure 1 is a front elevation of the belt-body disposed substantially as in use, and Fig. 2 is a side elevation of the belt-body extended out.

The deepest portion of the belt-body is off the center thereof, as illustrated at a a. The lower line or edge of the belt comprises the concave curve b, rising to the short reverse curve c as to one end, and as to the other end e, which is extended out to a greater extent than the end d, the curve c is of greater extent and on a longer arc. The upper edge 25 comprises the curve f on a greater arc than the curve b—that is, it is not as deep as the edge b—the curved edge f merging into the end curves g, where at the end e they taper into substantially parallel lines h.

The end e is pointed at i and provided with holes j, while the end e is short, abrupt, and squared.

Having described my invention, I claim—

The design for a belt-body, or similar article, substantially as herein shown and described.

Signed at the city, county, and State of New York this 18th day of October, 1900.

WILLIAM VITZTHUM.
